UNITED STATES PATENT OFFICE

2,122,874

APPARATUS FOR COMPRESSING FINELY DIVIDED SUBSTANCES

Allen D. Whipple, Alexandria, Ind., assignor to Johnson Laboratories, Inc., Chicago, Ill., a corporation of Illinois.

Application January 31, 1935, Serial No. 4,228

2 Claims.

(Cl. 18—5)

The invention relates to methods of and apparatus for compacting finely-divided materials, such as powdered metals, powdered bakelite, graphite, starch, sugar, clay, salt and in general, any material, or mixture of materials which is capable of being compressed into a coherent mass. The invention is especially useful in the manufacture of magnetic cores, such as are employed in high-frequency and other electrical circuits, wherein it is desirable that said cores shall each be homogeneous throughout, in order that they shall have desirable uniformity of electrical and magnetic characteristics. Said invention comprehends a method and an apparatus which admit of the uniform compression of all portions of such a substance and the consequent formation of a product having the same density throughout its entire mass.

These results are attained by the use of a plunger or plungers operating in a floating compression cell whose wall is movable with, instead of being fixed in relation to the substance enclosed thereby.

Heretofore, apparatus for compressing finely-divided materials have been provided with a movable plunger and a fixed or a positively-actuated compression-cell whose inner surface, during the act of compression, was frictionally engaged by the finely-divided material, the result being that the compressive energy acting upon the plunger was unequally applied to sequential portions of that material. For this reason, the parts of the product most remote from the plunger were rendered less dense than other parts thereof. This difficulty also was experienced with compressing apparatus embodying opposed movable plungers, whose products were less dense between than at the ends.

Certain prior-art devices for compacting finely-divided materials have been provided with movable cells, but these cells were actuated or so controlled by some other element, that friction between said materials and the walls of said cell was neither avoided nor minimized.

The new apparatus, herein disclosed, by eliminating, materially reducing or minimizing friction between the finely-divided material and the inner surface of the cell, produces a product which is of uniform density throughout, regardless of whether it embodies a single movable plunger, or opposed movable plungers.

The invention will best be understood if reference be had to the accompanying drawings, in which—

Figure 1 is a view in elevation of an appara-

tus embodying the invention, parts being broken away to reveal the compression cell and its associated elements; and

Figure 2 is a vertical sectional view of a modification, to an enlarged scale, taken on the line 2—2 of Figure 1.

These drawings illustrate only one of several types of apparatus in which the invention may be embodied, it being possible to incorporate said invention in any known apparatus containing 10 actuating devices for either a single compressional plunger or even opposed compressional plungers.

As shown, said apparatus embodies a suitable frame 1 upon or within which the actuating and actuated parts are mounted.

The apparatus is provided with a floating or movable cell 2, that is enclosed by a fixed guide 3 in which it has a free vertical movement, said cell being automatically held in its initial or idle position by a spring 4 which is of sufficient 20 strength to sustain the weight of the cell, and, consequently, will not materially impede its downward movement while the enclosed finely-divided material is being compressed; but any means which will sustain the weight of said cell 25 2 may be employed. In fact, the apparatus has been successfully operated without any sustaining means other than the hand of the operator which lightly grasped said cell 2 while a considerable number of compressed pellets were produced.

The cell 2 may be exteriorly beveled near its upper end, as shown at 2a in Figure 2 and, as shown in Figure 2, the fixed guide 3 may be provided with grooves 3a leading to outlet openings 3b, which carry away such portions of the finely-divided material as may unavoidably enter the space between said guide 3 and said cell 2, and, if retained therein, interfere with the return of said cell to its initial elevated position.

The apparatus includes an upper compressional plunger 5 and a lower ejector 6, which, during the act of compression, sustains the mass of finely-divided material, and, after compression is complete, operates to expel the pellet. The 45 actuating devices for this ejector 6 may be such that it will either remain stationary until the finely-divided material is fully compressed, or move upward to some extent toward the descending plunger 5 to thereby participate in the work 50 of compression.

Mounted in the upper part of the frame 1 is a shaft 7, having, at one end, a driving pulley 8, and, at the other end, provided with a beveled pinion 9 meshing with a further beveled pinion 35

10 that is mounted on a vertical shaft 11. This shaft 11 carries at its lower end a beveled pinion 12, meshing with a beveled pinion 13 carried by a horizontal shaft 14.

5 A cam 15 on this shaft 14 engages an anti-friction pulley 16 mounted in a hollow block 17. Secured to this block are upwardly-extending thrust rods 18 which, at each revolution of said cam 15, engage a vertically-movable block 19 upon which is fixedly supported a further thrust rod 20 extending upward within the fixed guide 3 and having a socket 21 in which the ejector 6 is suitably secured. A spring 22, surrounding the rod 20 and interposed between said block 19 and said fixed guide 3, operates to return said block 19 and its associated elements to their original positions in which they remain until they again are actuated by said cam 15.

The apparatus may be provided with a pressure-relieving device, which comprises four rods 23, threaded at 23a, and whose upper ends 23a are screwed into the frame 1, and whose lower ends are provided with adjustable nuts 24 which sustain springs 25 carrying a plate 26 through holes 26a of which the rods 18 freely extend. Rods 23 also extend freely through said plate 26. Nuts 23b borne by said screw-threaded rods 23, admit of the vertical adjustment of the plate 26 to thereby determine the altitudinal position of the block 19 during the period of compression.

The function of the springs 25 is to relieve the excessive downward pressure which would be produced if any compressed pellet should not be expelled from the cell before the introduction of material for a succeeding pellet.

30 The plunger 5 is actuated by a crank 27 which engages a pitman 28 swiveled at its lower end 29 to a vertically-movable block 30 that reciprocates in side guides 31, 31. Fixedly depending from said block 30, is a chuck 32 having a cavity 32a at its lower end in which the upper end of the plunger 5 is secured by a screw 32b.

In order to vary the initial position of said plunger 5, said pitman 28 may be provided with some suitable means for altering its length, such, for instance, as a screw 33 engaging the threads 33a of a cavity 33b with which the upper part 34 of said pitman is provided, the lower end of said screw being formed with a head 35 having a suitable swivel connection 36 with the block 30 to admit of the turning and consequent adjustment of said screw. Said head 35 has holes 35a, in any one of which a suitable instrument may be inserted when said screw is to be turned. Ease 45 of adjustment is attained by slitting, as at 34a, the upper part 34 of the pitman at its cavity 33b, and by providing it with perforated lugs 37 having bolts 37a which may be tightened or loosened as occasion may require.

50 The apparatus is provided with an oscillatory hopper 38 comprising a funnel 38a and an inclined chute 38b. Extending downward from said funnel is a post 38c the lower end of which is provided with a cavity 38d into which a pivot pin 38e extends.

Said oscillatory hopper 38 is moved to and from the position in which it will discharge portions of the finely-divided material into the compression cell, by a cam groove 39 on the shaft 7. This cam 55 groove engages and actuates a lever 40 pivoted at 40a, the lower end of this lever being connected by a link 41 to the chute of said hopper.

The movements of this hopper, produced by said cam groove 39, relatively to the movements of said plunger 5, and said ejector 6, respectively produced by the crank 27 and the cam 15, are such that said hopper remains in the idle position, shown in Figure 1, when the compression of the finely-divided material is taking place, and also while the compressed pellet is being ejected from the cell, and is moved to filling position while the ejector 6 is returning to its initial lowered position and a new charge is to be introduced into said cell.

The modification shown in Figure 2, generally involves the same elements as the embodiment of the invention illustrated in Figure 1 of the drawings, but in this construction means are provided for producing tubular pellets instead of solid pellets as illustrated in Figure 1.

In this modification, the plunger 5 and ejector 6 are tubular to cooperate with a core which is 20 a floating element having two aligned parts 2c, 2d, sustained by a spring, 22a, which, at its lower end, rests upon a fixed plate, 26 and, at its upper end, engages a shoulder of said part, 2d. Said two parts, 2c, 2d, are flexibly united by a ball and 25 socket joint, 2e, 2f, so that any possible lateral displacements of the lower part, 2d, will not tend to produce lateral displacements of said upper part 2c, which lateral displacements, if produced, would cause said upper part to force the ejector 6 30 against the inner wall of the floating cell 2 and impart thereto undesirable friction, or restrain its essential movements.

In this modification, the tubular element 20a, is of such size as to accommodate, not only the 35 lower part 2d of the aforesaid core and the spring 22a, but also a sleeve 19a, which, at its lower end, is fixed in said plate 26, the function of said sleeve being to divorce said spring 22a from the vertically-movable element 20a and to permit said 40 spring to operate without appreciable restraint.

The term "floating cell" is intended by me to mean a cell that is actuated in its movements by the frictional force set up by relative motion between the cell wall and the compression member 45 or members cooperating therewith, and is not actuated by an impelling element which imparts thereto its own movement, the result being that said cell moves, not continuously, but step by step during the period of compression.

Having thus described my invention, what I claim is:

1. An apparatus for compressing substances, including a cell for receiving substance to be compressed, means for compressing said substance in said cell, a core extending into said cell during compression, a supporting member for said core, a flexible connection between said core and said member, and devices for separating the compressed substance from said core. 60

2. An apparatus for compressing substances, including a cell for receiving substance to be compressed, means for compressing said substance in said cell, a core extending into said cell during compression, a supporting member for 65 said core, a ball and socket connection between said core and said member, and devices for separating the compressed substance from said core.
